ABSTRACT OF THE DISCLOSURE

Heddles for the harness of weaving looms with separating provisions at the warp controlling eyes of the heddles preventing nesting of the heddles.

BACKGROUND OF THE INVENTION

Field of the invention

This invention relates to loom harness and more particularly to the heddles in harness of the type used in water jet looms.

Description of the prior art

It has heretofore been proposed, in loom harness, to space portions of the heddles intermediate their ends and this has been effected by various provisions.

Configurations for such spacing of the heddles are shown by Kaufmann, U.S. Patents Nos. 1,090,858 and 2,426,456.

It has also been proposed, as in the patent to Kaufmann, No. 2,450,241, to provide bends in the body portions of the heddles above and below the warp eyes so that the heddles tend to separate.

SUMMARY OF THE INVENTION

It is the principal object of the present invention to provide an improved heddle construction at the warp eyes for providing a separation of the heddles at the warp eyes thereby eliminating nesting of the heddles.

It is a further object of the present invention to provide an improved heddle construction which is simple but effective for preventing nesting of heddles at their warp eyes, and particularly in water jet looms.

It is a further object of the present invention to provide an improved heddle construction in which, in a preferred embodiment, alternate heddles, at their warp eyes are shaped to prevent nesting.

Other objects and advantageous features of the invention will be apparent from the description and claims.

BRIEF DESCRIPTION OF THE DRAWING

The nature and characteristic features of the invention will be more readily understood from the following description taken in connection with the accompanying drawings forming part thereof, in which:

FIGURE 1 is a view in elevation of one of a pair of related heddles in accordance with the invention, the rods upon which the heddle is mounted being shown in section;

FIG. 2 is a view similar to FIG. 1 showing in elevation another of a pair of related heddles in accordance with the invention;

FIG. 3 is a front elevation of a pair of heddles of the type shown in FIGS. 1 and 2, and illustrating the separating action at the warp eyes, parts of the heddles being omitted; and

FIG. 4 is a fragmentary perspective view of the mid portions of a pair of related heddles.

It should, of course, be understood that the description and drawings herein are illustrative merely, and that various modifications and changes can be made in the struc-

2

ture disclosed without departing from the spirit of the invention.

Like numerals refer to like parts throughout the several views.

DESCRIPTION OF THE PREFERRED EMBODIMENT

Referring now more particularly to the drawings heddle rods 10 and 11 of well known type are shown, these being mounted as is well known in harness frames (not shown).

A multiplicity of heddles 12 and 13 are mounted on the heddle rods 10 and 11, in a well known manner.

The heddles 12 and 13 are preferably made of thin flat strips of metal, initially of a uniform width corresponding to the widest portion of the heddle. The central portion 14 of each heddle 12 or 13, and the end portions 15 are preferably the full width of the strip and the parts 16 of the heddles 12 and 13 are sheared down to a narrower width to provide greater flexibility in the heddles and to reduce the total weight of the harness.

The end portions 15 of each heddle 12 and 13 are each provided with a slot 18 for mounting on the rods 10 and 11 and the slots 18 may have central portions cut away on one side, as at 19, to permit free end to end movement of the heddles 12 and 13 on the heddle rods 10 and 11 and past any center braces and intermediate heddle rod supports, in a well known manner.

Alternate heddles of the heddles 12 and 13 may have spacing projections 20, of well known type, engaging straight portions of contiguous heddles to insure greater freedom of movement of the warp during shedding as well as to facilitate drawing in of the warp.

The central portions 14 of each of the heddles 12 and 13 may be provided with oppositely downwardly and upwardly pointing keyhole slots 21 and 22 for engagement by the drawing-in machine employed for entering the warp in the warp eyes.

The central portions 14 of each of the heddles 12 and 13 are provided with punched warp eyes 23 and 24 to receive and control the warp during the weaving operation.

One of the warp eyes of a related pair of heddles 12 and 13, such as the warp eye 23, has the shanks 25 thereof formed in bowed conformation and to a predetermined distance from and on opposite sides of the main plane of the central portion 14.

The other of the warp eyes of a related pair of heddles 12 and 13, such as the warp eye 24, has the shanks 26 thereof also in bowed conformation and to a different predetermined distance, in this instance less than the deformation of the shanks 25 from and also on opposite sides of the main plane of the central portion 14. The shanks 25 and 26 are preferably respectively offset in the same directions rather than in respectively opposite directions so that in successive heddles the engagement of one of the shanks 26 with a contiguous shank 25 is obviated by reason of the different shaping or curvature of the shanks, spacing of the remainder of the central portions 14 of the heddles 12 and 13 is effected and adherence of heddles 12 and 13 at the warp eyes 23 and 24 is prevented. At the same time relatively close spacing of the heddles 12 and 13 can be effected and the space within the harness frame utilized.

It will thus be seen that provisions have been made for attaining the objects of the invention.

I claim:

1. Loom harness comprising a plurality of heddles of thin flat strips of metal having top and bottom mountings, each of said heddles having a central portion intermediate the top and bottom mountings provided with a warp eye,

3

each of said warp eyes having its shanks offset in opposite directions from the main plane of the central portion,

the shanks of the warp eye of one heddle being offset to a greater extent in a predetermined direction than the corresponding shanks of the warp eye of an adjoining heddle thereby to space the heddles at their warp eyes.

2. Loom harness as defined in claim 1 in which said heddles have the corresponding shanks of successive heddles offset in the same direction.

3. Loom harness as defined in claim 1 in which successive heddles at the central portions have oppositely pointing keyhole slots.

4. Loom harness as defined in claim 1 in which

said heddles contiguous to the top and bottom mountings have additional spacer members.
